APPARATUS FOR SURFACING PAPER

Filed June 30, 1924

UNITED STATES PATENT OFFICE

JOSEPH MOSES WARD KITCHEN, OF EAST ORANGE, NEW JERSEY

APPARATUS FOR SURFACING PAPER

Application filed June 30, 1924. Serial No. 723,379.

The object of the invention is to enable the aim of my invention protected by my Patent No. 1,124,650, of May 1, 1917, to be practically applied.

5 The aim of the present invention is the product claimed in the cited patent, and having the same purpose, which was securing a more efficient cleansing of moisture and effete matters from the skin. In carrying out that 10 object, I aim to form on the surface of toilet papers, ridges, dams, bosses and concavities that will act in scraping, holding and removing adherent matters from the skin and which increases the moisture absorptive 15 power of; as well as to prevent the distensible stretching that is usual in crimped papers. This distensible stretching I prevent by having smooth surface lines of paper running in cross directions on one level but have irregularities of surface, molded into the interstices of the non-stretchable surface lines. My aim is to produce a paper that is more 20 soft, flexible, and more efficient in cleansing and in absorbing moisture than ordinary 25 smooth calendered tissue paper, and be more economical and sanitary in use.

In evolving the present method and apparatus, I find that it is desirable to manufacture a basic paper as a separate process, 30 such as ordinary calendered, smooth, dry, hard surfaced tissue.

In giving the ordinary toilet tissue or other paper the new surface character required in accomplishing the aim of this invention, the 35 basic paper must be sufficiently moistened to enable the surface to be molded into the desired form in being smoothed out and impressed into the concavities in the surfaces that would give the paper the desired change 40 in character. To retain the changed form of surface, it is necessary to more or less dry the paper after wetting it and before it is removed from the surface that is given the paper its new form of surface. The desired 45 form may be engraved or otherwise formed on the surface of a revolving cylinder having depressions into which the moistened, softened parts of the paper may be impressed by special forms of couch rolls having elastic, 50 soft or other impressing surfaces. But inas-

much as speed in drying the paper is a desideratum, I prefer to re-surface the paper upon a traveling endless wire-web of considerable length, so that a longer time for drying is taken than on a revolving cylinder. 55 This extended drying surface is also more economical of power than in running the paper on the web in contact with drying cylinders in the ordinary methods of drying paper tissues. The wire-web used, has a special surface such as gives the paper its designed changed form of surface. A very efficient form may be secured by merely molding the moistened paper upon an ordinary interwoven wire cloth-web having wire of 60 selected gauge, and mesh interstices between the interwoven wires of selected size.

A preferred embodiment of the invention is shown in the accompanying drawings, in which Fig. 1 schematically illustrates in vertical side view an apparatus for surfacing paper. Fig. 2 is a plan view of one end of the apparatus. Fig. 3 is a special form of compressing couch roll, drawn on a larger scale. Fig. 4 are washers that are used in building 70 up the surface of the couch roll. Fig. 5 is a side view of the wire web used in the apparatus, having a layer of paper resting on the upper surface of the web. Fig. 6 represents a vertical side cut of the paper, having 75 a surface formed on the wire web, and Fig. 7 is a fragment of the produced paper, indicating its surface arrangement of form, both as to ridges and depressions.

The reference characters indicate as follows: A and B are two drum-rollers on which the wire-web W runs. C are paper in-drawing rollers. D is a water tank. E is a water distributer. F is a water supply valve. G are water distributing rollers, and H is 80 a squeeze-impressing roll. I are paper retention rolls for holding the paper in place while drying. J are wire-web supporting rolls. K and L are steam pipes for heating the air for drying the paper on the web. M 85 is an idler for taking up the slack of the wire-web. N is a sliding weight for the idler. O are pressure-producing weights. P are cross ridge lines. Fig. 7 shows the paper surface off the web. Z are the drum shafts 90 100

that are affixed to the enclosing box which encloses the apparatus and conveys the heated air to the paper on the web. R are arms of pressure levers which press the rolls against the drum A. Fig 3 is the squeeze-roll drawn on a larger scale. H' are flanges which hold the elements of the squeeze roll in tight apposition. T are felt washers and U are cardboard washers, which when intervened and drawn together by the flanges, H', produce a desirable compressing surface for impressing the moistened paper into the concavities of the wire-web W. V is a motor. X is a drive belt connecting the motor with 10 and operating the drum B. Y is a drive pulley.

In carrying out the method, the dry basic paper is run onto the wire-web at the point where it is caught and drawn against the web on the drum A and held in place by the rolls C. The paper is wet with water drawn from the elevated tank D, and is dripped or sprayed thru small spray nozzles E or other means. The amount of water needed to be applied, is controlled by the valve E. The water may be sprayed or dripped onto the wet rolls G, which distribute the water on and commence to impress the paper into the concavities of the wire-web W. The complete impression of the moistened paper into the interstices of the wire-web is effected by the squeeze-roll H. A number of rolls of each kind may be used effectively in securing the new surface. The paper is dried in its travel to the drum roll B from which the paper is taken off and reeled in the ordinary way; and is later cut up into strips and sheets, and packed in rolls in the ordinary way.

I do not confine myself to the particular apparatus or method shown and described in the present application.

It will be obvious that moist paper can be taken directly from the paper making machine and given its embossment by ordinary embossing rolls, and then transferred onto and held in place on a long drying web; but for making a tissue paper having an unbroken substance of the tissue, a considerable amount of water must be used in moistening the paper before it is molded into the surface that will give it a permanent form. Paper can be given the form of a wire-web such as used in this invention, with very little or added moisture; but there is a usual probability of the tissue of the paper being broken. In preparing a paper for merely drying hands and face, such breakage of the tissue is not objectionable; and in such cases, the paper can be impressed with ordinary hard embossing rolls that are constructed with the features necessary in carrying out the aim of my Patent No. 1,124,650. It will also be obvious that various minor modifications of structure in the apparatus de-

scribed can be made, that will not depart from the spirit of the invention. Where breakage of the tissues of basic paper is undesirable, a soft squeeze-impressing-roll is necessary; but in some surfacing, a hard squeeze roll can be used. It is to be understood that the drums and rollers of the apparatus on which the wire cloth web is run are covered with some soft material, such as felt cloth, in which the interwoven wire work will rest without injury to the web, which is preferably made with tin coated flexible wire of such gauge and openness of mesh as will give the entire web sufficient flexibility to be curved around the end drums of the apparatus. Preferably, the surfaces of the small rolls C, G, I and J are felt covered, so as to exert a retaining pressure on the web of the paper while it is being moistened and dried.

What I claim as new is:

1. Apparatus for surfacing paper herein described, which consists of means for moistening a dry basic paper in running the paper on an endless wire-web, said wire-web, means for spreading the surface of and molding the moistened paper into irregularities in the surface of the wire-web, said irregularities in the surface of the wire-web, said means comprising a pressure roll having a soft elastic molding and pressure surface adjustable to the irregularities in the surface of the wire-web, and means for drying the impressed and molded paper while on the wire-web.

2. Apparatus for surfacing paper herein described, which consists of two end-holding-drum-rolls, an endless web running on the two rolls, said web being supported at a level running between the tops of the holding rolls by a plurality of supporting rolls, said supporting rolls, paper drawing and holding rolls, paper wetting and water spreading means for wetting the paper, moisture and impressing rolls, a finishing compression soft surfaced roll, paper retaining rolls running in connection with the supporting rolls, and means for applying heat to paper on the web until the paper is sufficiently dried to be removed from the web.

3. Apparatus for surfacing paper herein described, which comprises an endless wire-web running on revolving drum rollers, said drum rollers, means for running a dry paper tissue onto the wire-web, means for water-moistening the paper, means for spreading the moistening water over the surface of the paper on the wire-web, means for impressing the moistened paper into irregularities of surface of the wire-web, means for drying the paper while on the wire-web, and means for removing the paper from the wire-web after the paper has been dried.

4. Apparatus for embossing paper herein described, which consists of means for mois-

tening the paper uniformly over the surface of the paper and for definitely controlling the amount of moisture applied to the paper, means for embossing the paper and drying the embossed paper on a traveling web, said traveling web, said means comprising means for maintaining the web in a substantially horizontal plane during the travel of the web and for maintaining a determined tension of the web, and means for drying the paper by heatig air.

5 5. Apparatus for surfacing paper comprising means for moistening the paper and compressing the moistened paper into the irregularities of a fixed form of surface, said 15 fixed form of surface having irregularities of form, and means for drying the paper while it retains the irregularities of surface form.

20 6. Apparatus for embossing a smooth surfaced paper with raised ridges running at right angles to each other, and forming depressions on the interspaces between the ridges, said apparatus comprising a hard receptive 25 impressing surface and a cooperating soft impressing roll, and means for controlling the moisture and the heat of the paper during the functioning of the apparatus.

7. Means for surfacing paper which 30 comprises means for moistening the paper, means comprising a hard embossing surface, a soft impressing roll, and a continually traveling web for holding the moistened compressed paper and means for heating and drying the 35 paper while on the web.

8. Apparatus for giving a smooth paper surface indented lines running at right angles to each other on both sides of the paper, said apparatus comprising a hard surface containing elevations and depressions, a soft impressing roll adapting itself to the hard surface, means for automatically controlling pressure of the impressing roll against the hard surface, and means for moistening and drying 45 the paper.

9. Apparatus for surfacing paper comprising a web having indentations and elevations running parallel with the width of the paper, and indentations and elevations running at 50 right angles to the first named indentations, a pressure roll for pressing the paper into the indentations of the web, and means for exerting a regulated pressure on and against the first named features under an automatically 55 acting variable pressure, said apparatus producing embossed indentations and ridges on both sides of the paper running at right angles to each other.

60 10. Apparatus for embossing paper comprising a travelling web means for moistening the paper and feeding the paper between feed indrawing rolls in compressed contact with the paper, means for molding the moistened paper into depressions, and means for

quickly drying the paper without effacing the molded surface of the paper.

11. Means comprising a travelling web for giving a moistened paper embossed indentations and ridges running at right angles to each other, means for moistening a continually fed sheet of paper into the embossing structure of the apparatus, and means for drying with heated air the embossed moistened paper at the same rate of travel as that of the feeding of the paper.

12. Means comprising a travelling web for giving quadrilateral bosses to paper with depressed lines running at right angles to each other and between the bosses, said means comprising means for moistening the paper before forming the bosses, means for forming the bosses and means for completely drying the paper after the formation of the bosses without loss of form in the bosses.

13. Apparatus for giving irregularities of surface to paper which comprises a plurality of rolls, an indented surface, means for impressing the paper into the irregularities, a supporting traveling drying web, and means for retaining the paper on the web during the drying of the paper.
